The ornamental design for an offset housing assembly with vertical LEDs, as shown and described.

DESCRIPTION

FIG. 1 is a perspective view of the offset housing assembly with vertical LEDs of the present invention;

FIG. 2 is a left side view of the offset housing assembly with vertical LEDs shown in FIG. 1;

FIG. 3 is a front view of the offset housing assembly with vertical LEDs shown in FIG. 1;

FIG. 4 is a right side view of the offset housing assembly with vertical LEDs shown in FIG. 1;

FIG. 5 is a back view of the offset housing assembly with vertical LEDs shown in FIG. 1;

FIG. 6 is a top view of the offset housing assembly with vertical LEDs shown in FIG. 1; and,

FIG. 7 is a bottom view of the offset housing assembly with vertical LEDs shown in FIG. 1.

The portions of the offset housing assembly with vertical LEDs as shown having broken lines form no part of the claimed design.
